Harry J. Criner INVENTOR.

UNITED STATES PATENT OFFICE.

HARRY J. CRINER, OF BURLINGTON, IOWA, ASSIGNOR TO L. V. KOKES AND E. L. VOGELTANZ, OF ORD, NEBRASKA.

COMBINED DRIVING MECHANISM FOR WASHING MACHINES AND WRINGERS.

Application filed December 27, 1926. Serial No. 157,291.

My invention relates to a combined driving mechanism for washing machines and wringers and the objects of my invention are:

1. To provide a simplified combination 5 driving mechanism for a washing machine and wringer which will furnish the necessary differences in driving speeds and provide for the reciprocating rotation of the washer shaft, with the smallest practicable number 10 of parts.
2. To provide a driving mechanism which will be enclosed and can be run in oil so as to reduce friction and noise with improved means for throwing it into and out of gear.
- 15 3. To provide a driving mechanism which will be out of the way and with all gears enclosed.

I attain these objects by the mechanism illustrated in the accompanying drawings, in 20 which,—

Figure 1 shows a top or plan view of my improvement; Fig. 2 is a side elevation showing the left end of the housing cut away to disclose the bevel gears and other parts; Fig. 25 3 is a top or plan view of my mechanism with the top of the housing cut away to disclose the interior parts. Fig. 4 is a detail showing the cam, 25, and rocker shift lever, 19; Fig. 5 is an additional detail showing the 30 relative position of the cam and rackbar when in operative position.

My invention includes a housing, 1, with a cover-plate, 2, secured to the bottom thereof. The housing is preferably of castiron or 35 aluminum and the cover-plate may be secured thereto by any of the means now in common use for such purposes and the adjacent surfaces of the housing, 1, and the cover-plate, 2, should be ground to form a close fit or provided with a gasket or sealed in any other 40 desired manner.

The housing is provided with lugs one of which is shown at 36, by which it may be secured to the frame of the washing machine 45 or it may be mounted upon brackets or other supports as desired. The housing is mounted in such a way that the washer drive shaft, 7, lies in the line of the center of the tub of the washing machine and the shaft, 7, extends 50 upwardly into the tub of the washing

machine. The housing is also so mounted that the wringer shaft, 8, is outside of the line of the tub and it extends upwardly along one side of the tub of the washing machine to the wringer head.

55 My apparatus is designed primarily to be driven by an electric motor, 16, but may be driven by any other suitable means. A belt wheel, 13, is mounted upon the free end of the drive shaft, 10, which is mounted in suitable bearings, 11 and 11^a, formed integral with the housing, 1. A small bevel gear or pinion, 30, is mounted upon the other end of the main drive shaft, 10, within a housing, 12, formed integral with the housing, 1. A 60 large bevel gear, 31, is mounted upon the lower end of the wringer shaft, 8, in continuous mesh with the pinion, 30.

65 A crank pin, 32, is suitably secured in the bevel gear, 31, and has one end of the rack, 28, pivotally mounted thereon. The opposite end of the rack, 28, is provided with a series of teeth corresponding to the teeth in the spur gear, 29, mounted upon the lower end of the washer shaft, 7, and within the housing, 1, 70 the housing, 1, to be provided with bosses or enlargements, 5 and 6, to form suitable mountings for the shafts, 8 and 7, respectively.

75 The rack, 28, is held in mesh with the spur gear, 29, by the larger end of the head of the cam, 25. The cam, 25, operates to hold the rack, 28, into mesh with the spur gear, 29, when in one position and to permit the rack to be drawn away from the spur gear by the 80 spring, 33, when in another position. The cam, 25, is formed integral with a flange, 27, separated from the head by a deep groove, 26, in which the head, 21, of the rocker lever, 19, is mounted. The rocker lever, 19, is pivoted 85 upon the pivot, 20, secured in a boss, 4, of the housing, 1. The rocker lever, 19, is secured to the lower end of the shift rod, 18, by washers, 21 and 22, and cotter keys, 23 and 24, and the upper end of the shift rod, 18, is provided 90 with a handle, 18^a, which is adapted to project outwardly through the washing machine housing so that it can be manually raised or lowered to shift the cam, 25, and throw the rack, 28, and spur gear, 29, out of and into 95 100

mesh, it being understood that the rack, 28, is drawn out of mesh by the spring, 33, one end of which is secured to the rack, 28, and the opposite end of which is secured to a bolt, 34, 5 which passes through the outer end of a lateral extension, 3, of the housing, 1, and is held in place by a nut, 35, upon the inner end of the bolt, 34. An opening, 17, is provided in the top of the housing, 1, through which 10 the shift rod, 18, passes.

In the operation of my device, the apparatus is mounted within the base of the washing machine with the shaft, 7, projecting into the tub of the washing machine and connected with the dolly or other stirrer and the wringer shaft, 8, is connected to the wringer 15 in any of the usual ways.

The shift lever handle, 18^a, is then pressed downward which raises the cam, 25, and permits the spring, 33, to draw the rackbar out 20 of engagement with the spur gear, 29. The motor, 16, is then started and through the belt, drives the belt wheel, 13, and with it the main shaft, 10, pinion, 30, and bevel gear, 31, thus putting in motion the wringer shaft. The shift rod handle, 18^a, is then drawn up 25 forcing the cam, 25, downwardly so that the larger portion of its head forces the rack, 28, into engagement with the spur gear, 29, 30 which drives the washer dolly or stirrer through the shaft, 7.

The rotary motion of the shaft, 8, is continuous in one direction, but the rackbar, 28, causes the spur gear, 29, to rotate alternately 35 in opposite directions.

The pinion, 30, bevel gear, 31, and spur gear, 29, are so proportioned as to give the desired speed for the shafts, 8 and 7, in proportion to the speed of the motor, 16.

40 An oil hole, 1^a, is provided in the housing, 1, through which oil may be poured to fill the housing, 1, to the desired height and the oil hole may be closed by a screw plug, 1^b, or other suitable means.

45 I claim:

1. A combined driving mechanism for a washer and wringer comprising a tub, a housing, a drive shaft mounted thereon having one end extending into the housing and fitted with a pinion, a bevel gear mounted within the housing in mesh with the pinion, a crank pin united to the bevel gear, a vertical drive shaft mounted in the housing and extending into the tub of the washer, a spur gear mounted within the housing upon the lower end of the vertical drive shaft, a rackbar having one end pivotally mounted upon the crank pin and its opposite end mounted adjacent the spur gear, a tension spring having one end connected to the rackbar and its opposite end secured to the housing and adapted to normally hold the rackbar out of engagement with the spur gear, a cam mounted in the housing adjacent the toothed end 60 of the rackbar and having a curved face

adapted to force the rackbar into engagement with the spur gear when in one position and to permit the rackbar to be drawn away from the spur gear when in its opposite position, a manually operable shift lever extending upwardly through the housing, a rocking lever pivoted within the housing having upon one end a head adapted to engage and operate the cam, and its opposite end united to the lower end of the manually operable 75 shift lever.

2. In a driving mechanism for washing machines, a housing, a shaft mounted therein and having a gear wheel mounted upon the end thereof, a crank pin united to the gear wheel, a rack-bar having one end pivotally mounted upon the crank pin, a pinion and shaft mounted in the housing adjacent the toothed portion of the rack-bar, a spring connected to the rack-bar and the housing 80 adapted to hold the rack-bar out of engagement with its adjacent pinion, and a cam, having an inclined face mounted adjacent the rack-bar opposite the pinion and slidably in a plane at right angles to the plane of 85 movement of the rack-bar, and adapted to hold the rack-bar in engagement with the pinion when in one position and to permit it to be drawn away from the pinion when 90 in its opposite position.

3. In a driving mechanism for washing machines, a housing, a shaft mounted therein and having a gear wheel mounted upon the end thereof, a crank pin united to the gear wheel, a rack-bar having one end pivotally mounted upon the crank pin, a pinion and shaft mounted in the housing adjacent the toothed portion of the rack-bar, a spring connected to the rack-bar and the housing 100 adapted to hold the rack-bar out of engagement with its adjacent pinion and a tapered cam having an inclined face mounted adjacent the rack-bar opposite the pinion and slidably in a plane at right angles to the plane 105 of movement of the rack-bar, and adapted to hold the rack-bar in engagement with the pinion when in one position and to permit it to be drawn away from the pinion when 110 in its opposite position, and manually operable means for throwing the larger portion 115 of the cam into and out of engagement with the rack-bar.

4. In a driving mechanism for washing machines, a housing, a shaft mounted therein and having a gear wheel mounted upon the end thereof, a crank pin united to the gear wheel, a rack-bar having one end pivotally mounted upon the crank pin, a pinion and shaft mounted in the housing adjacent the toothed portion of the rack-bar, a spring connected to the rack-bar and the housing 120 adapted to hold the rack-bar out of engagement with its adjacent pinion, a tapered cam having an inclined face mounted adjacent the rack-bar opposite the pinion and slidably in 125

a plane at right angles to the plane of movement of the rack-bar, and adapted to hold the rack-bar in engagement with the pinion when in one position and to permit it to be drawn away from the pinion when in its opposite position, and a rocking lever pivotally mounted within the housing having one end

embracing the cam and its opposite end linked to a handle by which same may be manually operated.

In testimony whereof he affixes his signature.

HARRY J. CRINER.
